[57] CLAIM

The ornamental design for an adjustable lounge chair, as shown and described.

DESCRIPTION

FIG. 1 is a front perspective view of an adjustable lounge chair showing my design;

FIG. 2 is a front elevational view;

FIG. 3 is an elevational view showing one of the two identical sides;

FIG. 4 is a side view of the chair in fully extended position;

FIG. 5 is a side view of the chair as shown in FIG. 3 wherein one of the headrest members is shown in a downturned position; and

FIG. 6 is a side view of the chair as shown in FIG. 4 wherein one of the headrest members is shown in a down-turned position.
